Patented Sept. 12, 1967

208,565

MEAL SERVING UNIT

Rudolph Leonardo, McKeesport, Pa., assignor to Beef-Eater's Steak-on-a-Skillet, Inc., a corporation of Pennsylvania

Filed Nov. 23, 1966, Ser. No. 4,784

Term of patent 14 years

(Cl. D44—10)

Fig. 1

Fig. 2

Fig. 3

Fig. 4

Fig. 5

Fig. 6

FIG. 1 is a perspective view of a meal serving unit showing my new design;

FIG. 2 is a rear elevational view thereof;

FIG. 3 is an end elevational view thereof;

FIG. 4 is a perspective view of a meal serving unit, showing another form of my new design wherein the oval depression is omitted.

FIG. 5 is a front elevational view thereof; and

FIG. 6 is an end elevational view thereof.

I claim:

The ornamental design for a meal serving unit, as shown and described.
